A. E. GOLDSPIK.
PIANO PLAYER CONTROL.
APPLICATION FILED JAN. 20, 1919.

1,317,572.

Patented Sept. 30, 1919.

UNITED STATES PATENT OFFICE.

ARCHIBALD EATON GOLDSPINK, OF KENTISH TOWN, LONDON, ENGLAND.

PIANO-PLAYER CONTROL.

1,317,572.

Specification of Letters Patent.

Patented Sept. 30, 1919.

Application filed January 20, 1919. Serial No. 272,043.

To all whom it may concern:

Be it known that I, ARCHIBALD EATON GOLDSPINK, a subject of the King of England, residing at Kentish Town, London, 5 England, have invented certain new and useful Improvements in Piano-Player Controls, of which the following is a specification.

This invention relates to piano-player controls of the type wherein a manually operated control-lever is arranged to rock about a horizontal axis to control one or more parts of the mechanism, for example the loud pedal or the motor for driving the 10 music roll, and is operatively connected with a valve for controlling some other part of the mechanism, for example a pneumatic device for increasing or decreasing the playing force of a certain number of pneumatics. 15 The invention has for its primary object to provide a simplified lever control apparatus of the kind described by means of which the several operations can be selectively or collectively carried out by rocking 20 levers without removing the hand from a main control-lever. Another object is to extend the range of operation of the simplified lever-control apparatus and to provide that more than three operations of the 25 kind referred to can be selectively or collectively carried out without removing the hand from the same main control-lever.

Lever-control apparatus of the type described according to the invention comprises 30 the combination with a main control lever, operatively connected to one or more ports of the mechanism, of two auxiliary levers, one at each side thereof, fulcrumed thereon and controlling ports in the lever for air- 35 ducts, each of which communicates with a pneumatic action to regulate a part of the mechanism, for the purpose of enabling the operator to control several parts of the mechanism by rocking a group of more than two 40 levers without removing his hand from the main lever.

Preferably the auxiliary levers are provided with tail-pieces which lie on the opposite side of the fulcrum point to that occupied by the main body of the levers and cover the ports to be controlled, with or without the levers being made of channel section to partially embrace the control lever.

The lever may be movable endwise along its fulcrum axis and operatively connected

to impart movement thereby to other controlling devices, for example, a piston-valve to close one or more air-ducts connected with the pneumatic action; or the lever may be 60 fast upon a rocking-shaft which constitutes a piston-valve and controls ports pierced in the walls of the bearing for the said rocking-shaft, which ports communicate by conduits with the pneumatic action. 65

One embodiment of the invention and modifications thereof are diagrammatically illustrated by way of example in the accompanying drawing wherein:

Figure 1 is a front elevation showing one 70 form of the improved control lever, and

Fig. 2 is a side elevation thereof, partly in section;

Fig. 3 is a side elevation, partly in section, showing a modified construction comprising an axially slideable rocking shaft; 75

Fig. 4 is a side elevation of another modified construction wherein the rocking-shaft and its sleeve constitute a piston-valve, and

Fig. 5 is a side elevation, partly in section, 80 showing another modification wherein the parts of the air-ducts in the rocking-shaft are arranged concentrically one within the other.

Similar letters designate similar parts in 85 all of the views.

Referring first to Figs. 1 and 2, a hand-lever A is fast upon a rocking-shaft B which is carried by the sleeve G mounted in supports H. The hand-lever A constitutes the 90 main control-lever and its extremity A¹ is made crescent-shaped to constitute a finger-piece. To opposite sides of this lever are pivoted at C¹ intermediately of their ends two auxiliary levers C, so situated, one on 95 either side of the main lever, that the operator can readily actuate them without releasing his hold on the main lever. The main lever is of rectangular cross-section, and the auxiliary levers are of channel section so as to partly encircle it. The pivot-pins C¹ pass through the side walls of the 100 channel.

By means of springs D the heads C² of the auxiliary levers are forced outward from 105 the head of the main lever, thereby causing their tail parts C³ to lie upon the body of the said main lever so as to close ports E situated therein and near to its fulcrum. The ports communicate first with longitudinally disposed air-ducts or conduits F in the 110 rocking-shaft B of the main lever and then

with separate tubes J, the ends of which are flexibly connected to their corresponding parts, for example the motor regulating device, or the cutting-out device connected to 5 the wind-trunk.

The rocking-shaft B of the main lever A carries an operating arm K, mounted on a part of the shaft B located outside the sleeve G. This arm will be connected by a 10 tie or rod to the same part as that controlled by the arm K in the construction shown in Fig. 3 which will now be described.

In this modified construction the operating-arm K on the rocking-shaft B is provided for the control of the other parts of 15 the mechanism, such for example as the loud pedal or the starting or reversing mechanism for the music-roll, and will be connected thereto in the usual manner by a tie or rod. In this construction, the rocking-shaft in addition to being rotatably mounted is also slidable axially in the sleeve G, which carries it. By means of this axial movement other mechanism can be operated 20 by the movement of the lever A, for example, it may operate a piston-valve L constructed to close one or more tubes J¹ in communication with the pneumatic action, which tubes are terminated by ports M¹ 25 pierced in the casing M of the piston-valve. The piston-valve may be operatively connected with or concentrically-mounted upon the fulcrum-shaft. In this construction the tubes J might be connected, for example, to 30 actions controlling mechanism for accenting the base or treble, while the tubes J¹ might be connected, for example to devices for retarding and accelerating the motor.

In the modified construction shown in 40 Fig. 4, the rocking-shaft B and the sleeve G which carries it are used, respectively, as the piston-valve and the casing appertaining thereto; the ports terminating the above mentioned air-ducts J¹ are pierced at 45 G¹ in the sleeve so that they can be closed by sliding the shaft B.

In the modification shown in Fig. 5, the rocking-shaft B¹ consists of a tube having closed ends; the interior of this tube communicates with one of the ports E in the main lever A, and, by way of an outlet B² at the closed end of the rocking-shaft and a tube J connected thereto, with its allotted part of the pneumatic action, so that the interior of the tubular shaft forms one of the 50 ducts F shown within the rocking-shaft A in the construction illustrated in Figs. 1 and 2. The second duct in this modification consists of a tube J² within the hollow rocking-shaft extending airtight through the closed 55 end of the rocking-shaft to unite with the corresponding part of the pneumatic-action and at its inner end is connected to the second port E in the main lever. The parts 60 of the air-ducts in the rocking shaft are 65

thus arranged one in the other in this construction.

Owing to the construction of the control-lever according to this invention it will be seen that it can be moved about its axis on either side of its middle position and simultaneously or separately it can also be moved axially by the use of one finger only, and furthermore, either or both of the two auxiliary side levers can be actuated by the other fingers of the hand. As each of these movements is transmitted to different parts of the action, the operator can thus actuate one or many of the regulating devices connected with player-pianos without removing his hand from the lever.

It will be understood that the auxiliary levers may be mounted upon the main lever either at the sides to which the lever is rocked, or at the sides to which it is moved axially or endwise, the axes of the auxiliary levers being then in the first case disposed parallel to, or in the second case transversely of the axis of the main lever.

What I claim as my invention and desire to secure by Letters Patent is:—

1. In lever-control apparatus of the character described, the combination with a support and a shaft mounted to rock therein, of a main control lever which is fast on the shaft and has a free end shaped for engagement with one digit of one hand of the operator, said lever having two ports which open at one end into two opposite sides thereof, air-conduits connected one to the other end of each port, and two auxiliary levers fulcrumed to rock on opposite sides of the main control-lever and arranged each to control the former end of one of said ports, each auxiliary lever having a free end situated in proximity to the said free end of the main lever and so positioned that each can be operated by another digit of the same hand of the operator while the said first digit is resting on the shaped end of the main lever.

2. In an automatic musical instrument, lever-control apparatus comprising, in combination, a support, a hollow shaft mounted therein to rotate about its longitudinal axis, a single-ended control-lever having one end fast on the shaft and having two ports formed in opposite sides of the lever and opening directly into the hollow shaft, a pair of air-conduits connected one to each port in the shaft, and two auxiliary levers mounted to rock on opposite sides of the said control-lever and arranged each to control one of said ports with one end, and each with its other end in such positional relation to the free end of the control-lever that all three levers can be actuated simultaneously by the digits of one hand of the operator.

3. In an automatic musical instrument

lever-control apparatus comprising, in combination, a support, a hollow shaft mounted therein to turn about its longitudinal axis, a single-ended control-lever having one end 5 which is fast on the shaft and having two ports formed in opposite sides of the lever and opening directly into the hollow shaft, a pair of air-ducts extending into the shaft and connected one to each port, and two 10 spring-controlled auxiliary levers mounted to rock on opposite sides of the said control-lever and arranged each to control one of said ports with one end, and each with its other end in such positional relation to the 15 free end of the control-lever that all three levers can be actuated simultaneously by the digits of one hand of the operator, each auxiliary lever being of channel section and arranged to partially embrace the control-lever.

4. In an automatic musical instrument, lever-control apparatus comprising, in combination, a support, a hollow shaft mounted therein to rotate about and to slide in the direction of its longitudinal axis, a single-ended control-lever having at one end, which is fast on the shaft, two ports situated in opposite sides of the lever and opening directly into the hollow shaft, a pair of air-ducts connected one to each port in the shaft, two auxiliary levers mounted to rock on opposite sides of the said control-lever and arranged each to control one of said ports with one end, and each with its other end in such 35 positional relation to the free end of the control-lever that all three levers can be actuated simultaneously by the digits of one hand of the operator; and a set of air-ducts each adapted to be connected to a pneumatic action arranged to be controlled by the longitudinal movement of the shaft.

5. In an automatic musical instrument, lever-control apparatus comprising, in combination, a support, a hollow shaft mounted 40 therein to rock about and to slide in the di-

rection of its longitudinal axis, a single-ended control-lever having at one end, which is fast on the shaft, two ports formed in opposite sides of the lever and opening directly into the hollow shaft, a pair of air-ducts connected one to each port in the shaft, two auxiliary levers mounted to rock on opposite sides of the said control-lever and arranged each to control one of said ports with one end, and each with its other end in such 50 positional relation to the free end of the control-lever that all three levers can be actuated simultaneously by the digits of one hand of the operator, a set of air-ducts each adapted to be connected to a pneumatic action, and a controlling device arranged to be controlled by the longitudinal movement of the shaft and adapted to control said set of air-ducts.

6. In an automatic musical instrument, lever-control apparatus comprising, in combination, a support, a hollow shaft mounted therein to rock about and to slide in the direction of its longitudinal axis, a single-ended control-lever having at one end, which is fast on the shaft, two ports formed in opposite sides of the lever and opening directly into the hollow shaft, a pair of air-ducts connected one to each port in the shaft, two auxiliary levers mounted to rock on opposite sides of the said control-lever and arranged each to control one of said ports with one end, and each with its other end in such 70 positional relation to the free end of the control-lever that all three levers can be actuated simultaneously by the digits of one hand of the operator, a controlling device comprising a valve-casing having ports each adapted to be connected to a pneumatic action, and a piston-valve carried by the 75 shaft, and movable in said casing, and arranged to control the ports in the latter when the shaft is slid longitudinally.

In testimony whereof I affix my signature.

ARCHIBALD EATON GOLDSPIK.
